UNITED STATES PATENT OFFICE

148,827

DESIGN FOR A DRILL PRESS

Clifford Brooks Stevens, Milwaukee, Wis., assignor to Rockwell Manufacturing Company, Pittsburgh, Pa., a corporation of Pennsylvania

Application September 6, 1946, Serial No. 133,095

Term of patent 14 years

(Cl. D63—1)

To all whom it may concern:

Be it known that I, Clifford Brooks Stevens, a citizen of the United States, residing in Milwaukee, in the county of Milwaukee and State of Wisconsin, have invented a new, original, and ornamental Design for Drill Press, of which the following is a specification, reference being had to the accompanying drawing, forming a part thereof.

Figure 1 is a front elevational view of a drill press embodying my new design.

Figure 2 is a left side elevation of the drill press of Figure 1, and

Figure 3 is a view in rear perspective of the drill press of Figure 2.

The characteristic features of the design for

drill press disclosed reside in the pulley guard on top, the head portion thereunder and the base portion, having the configuration and appearance shown.

I claim:

The ornamental design for a drill press, as shown and described.

CLIFFORD BROOKS STEVENS.
